United States Patent Office

JOSEPH ROBLEY, OF BROOKLYN, NEW YORK, ASSIGNOR TO WILLIAM I BRASHER & CO., OF SAME PLACE.

Design No. 4,711, dated March 14, 1871.

DESIGN FOR A FLOOR OIL-CLOTH PATTERN.

The Schedule referred to in these Letters Patent and making part of the same.

To all whom it may concern:

Be it known that I, JOSEPH ROBLEY, of the city of Brooklyn, Long Island, county of Kings and State of New York, have invented or produced a new and original Design for a Pattern to be printed upon Floor Oil-Cloths in colors similar to those painted on the rawings accompanying this specification, or in other colors substituted in the place of those painted on the rawings herewith; and I do hereby declare that the rawings accompanying this specification do give and convey, to any one skilled in the art of manufacturing oor oil-cloth, a thorough description of the nature of my invention, and are sufficient to enable any one skilled in the art of manufacturing floor oil-cloth to use my invention.

What I claim as my invention, and desire to secure by Letters Patent, is—

The configuration of the design hereunto annexed when made by being wrought upon floor oil-cloth, the form similar to the drawings accompanying th specification.

JOSEPH ROBLEY.
